UNITED STATES PATENT OFFICE.

WILLIAM F. PACKARD, OF BROCKTON, MASSACHUSETTS.

EDGE-FINISHING MACHINE.

1,317,452.

Specification of Letters Patent. Patented Sept. 30, 1919.

Application filed February 5, 1918. Serial No. 215,751.

To all whom it may concern:

Be it known that I, WILLIAM F. PACKARD, a citizen of the United States, residing at Brockton, in the county of Plymouth and 5 State of Massachusetts, have invented a new and useful Improvement in Edge-Finishing Machines, of which the following is a specification, reference being had therein to the accompanying drawings.

10 This invention relates to edge finishing machines and more particularly to machines and devices for finishing the edges of leather and other materials.

The main object of my invention is to 15 provide a finishing machine which is durable, highly efficient, simple in construction and operation, and capable of being operated by relatively unskilled workmen.

Another object of the invention resides in 20 the provision of means for holding the work operated upon by the machine and in means for feeding the work so held.

Other objects will be in part obvious and 25 in part particularly pointed out and described hereinafter.

The invention consists of the various features of construction, combination of elements and arrangements of parts which will be exemplified by the construction herein- 30 after set forth and the scope of the application of which will be indicated in the following claims.

In the accompanying drawings, wherein 35 is shown one of the various possible embodiments of the invention:

Figure 1 is a view in side elevation of a 40 finishing machine embodying the invention; Fig. 2 is a top plan view of the same; Figs. 3 and 4 are top plan views of different pattern feed clamps; and Fig. 5 is an enlarged sectional view of one of the pattern feed clamps shown in operative relation with the table and finishing tool.

Briefly, the preferred embodiment of my 45 invention contemplates a machine having a suitable rotating tool for finishing the edge of material brought in contact therewith, a suitable patterned clamp for holding the material in such manner that the edge cannot be 50 bent or deflected when brought into contact with the finishing tool; said machine and said clamp being provided with means whereby the clamp is fed progressively in order to present the entire edge of the ma-

terial progressively to the action of the rotating finishing tool.

Referring now more particularly to the drawings, a bed is indicated at 1 supported by suitable uprights or legs 2 carrying a work table 3. Mounted on the upper part 60 of the bed 1 is an overhanging arm 4 terminating at its outer end in upper and lower yoke portions 5 and 6. An edge finishing tool which is indicated generally at 7 comprises a comparatively long spindle 8, a 65 pair of journal blocks 9 and 10, a driving pulley 11 formed on the upper end of a sleeve 12, an annularly grooved collar 13 and a finishing or burnishing iron 16 fixed to the lower end of the spindle 8. The upper journal block 9 is pivotally mounted within oppositely disposed walls 17 of the upper yoke 5 by means of supporting pins 18 threaded into the walls 17 and having conical bearing points adapted to engage with similar 70 recesses formed in the block 9. The bearing block 10 is arranged within oppositely disposed walls 20 of the lower yoke portion 6 and is provided with arcuate grooves 21 concentric with the pivot points 18 and 80 adapted to receive pins 22 tapped in either side of the yoke to project into the grooves 21. It is to be understood that the spindle 8 may rotate freely in the bearing blocks 9 and 10; the sleeve 12, however, carrying 85 driving pulley 11, is arranged between the bearing blocks 9 and 10 and adapted for rotative movement with the spindle 8 by means of a pin 24 projecting diametrically through the sleeve 12 and through a vertical slot 25 90 provided in the spindle 8. The spindle, therefore, is adapted for vertical movement relatively to the sleeve 12. The annularly grooved collar 13 is fixed to the spindle 8 and is adapted to be engaged in its groove 95 by operating pins 30 extending inwardly from opposite walls of a yoke 31 which is formed in an arm 32 of a bell-crank-operating lever 33, which in turn is pivoted to an 100 upstanding ear or lug 34 formed on the overhanging arm 4. The other arm 35 of the bell-crank-operating lever serves as a handle by which the lever may be moved about its pivot 36 to move the finishing tool 16 into and out of operative position. A bowed 105 leaf spring 37 is adapted to yield to permit movement of the handle from one position to the other and serves, as will be obvious,

to coöperate with a projection 38 on the lever to yieldingly lock the operating means in either of the two positions.

The overhanging arm 4 is formed with a bore 40 extending inwardly from the lower yoked portion 6, which bore is adapted to receive an expansile spring 41, one end of which seats upon the bearing block 10 and the other end of which reacts against the end of the bore 40. Also, there is provided at the outer end of the lower yoked portion 6 an end cap 42 attached to the opposite end walls of the lower yoked portion by means of screws 43. This cap is bored to receive an expansile spring 44 similar to the spring 41 which bears on an opposite side of the bearing block 10 and reacts upon an adjustable follower 45, the position of the latter in the bore being governed by means of a screw 46 having a knurled operating head 47. Attached to a depending projection 50 of the end cap 42 and lying in a horizontal plane is a guard or shield 48 above which the finishing iron 16 is adapted to retract when the mechanism is in inoperative position.

From the foregoing it will be noted that the fixed annularly grooved collar 13 is adapted to bear against the bearing block 9, which is pivotally mounted and held against vertical displacement, so that downward movement of the spindle is limited by the coöperation of said block and said collar; and that the bearing block 10 is adapted to oscillate slightly about the point 18 as a pivot, but this block is normally held in a definite but yielding position due to the application of spring pressure on either side thereof; that the spindle 8 has a range of substantially vertical movement relatively to the blocks 9 and 10 and the sleeve 12, and that the sleeve 12 and collar 13 are adapted for rotary movement with the spindle 8.

Mounted below the bed 1 in suitable bearings is a main shaft 52 having fixed thereon pulleys 53 and 54, the former being adapted to receive power from any suitable source and the latter being adapted to transmit said power through the endless belt 55 which passes around the pulley 54 over the idlers 56, journaled in the overhanging arm 4 and around the pulley 11 formed on the sleeve 12. This main shaft is provided with a threaded portion 57 adapted for engagement with a worm wheel 58 which in turn is fixed on the end of a short vertical shaft 59 projecting upwardly through the bed 1 and having fixed thereon at its upper end a feed roller 60 of substantial diameter. It should be observed that by means of the power transmitting devices just described, the spindle 8 will be operated at comparatively high speed while the feed roller 60 is operated at low speed.

The bore 61 in the end of the bed 1 is

adapted to slidably receive a block 62 which carries a stem 63 which in turn has loosely mounted thereon a roller 64 of small diameter. A groove 65 is provided in the bed 1 and table 3 permitting a sliding movement 70 of the block, its stem and said roller relatively to the bed and table. The block and roller are, however, normally urged in a direction toward the main feed roller 60 by means of a spring 66 having one end 75 bearing upon the block and the other end reacting upon the plate 67 secured to the end of the bed 1 opposite the bore 61. In order to heat the operating tool 16 and maintain it at a high temperature and thereby 80 burnish the edge of the material being finished, a gas burner 68 is provided having its nozzle in close proximity to the tool 16.

The tool operation and mechanism having been described the construction of a preferred form of pattern clamp follows.

The pattern feed clamp comprises upper and lower clamping templets 70 and 71 hinged together as indicated at 72 and provided with a suitable locking device, as indicated at 73, consisting of a hasp 74 secured to the lower member 71 and adapted to receive a wedge 75. The lower member is equipped with a rail 76 corresponding in general configuration to the edge to be finished. This rail is adapted to rest upon the table 3 in operation and is receivable between the coöperating feed rollers 60 and 64, whereby a slow feed action is transmitted to the pattern.

In operation, the handle 35 having been thrown to the left to raise the spindle 8, the pattern, having securely clamped between the upper and lower members thereof a vamp or other article, the edge of which it is desired to finish, is moved into position to engage one end of the feed rail 76 with the feed roller 60. The roller 64 being urged with considerable pressure against the other side of the rail, and if desirable, being provided with some friction coating, imparts a slow feeding movement to the pattern. The handle 35 is then moved to the right in Fig. 1, whereby the spindle 8 is lowered and the tool 16 urged against a 115 projecting edge 80 of the vamp. The spindle is continuously rotating at high speed and as the pattern or templet travels on the rails 76 at comparatively low speed with the bur- 120 nisher 16 bearing against the edge 80, the latter is given a highly polished appearance and even form. It should be noted that in manipulating the pattern toward and from the table it is unnecessary to discontinue the rotation of the spindle or the feed mecha- 125 nism. The work being finished is securely held between the clamping members by means of the wedge 75, the rail 76 insuring a proper positioning of the work opposite the tool and supporting the pattern in such 130

a way that the same is automatically guided and controlled.

As many changes could be made in the above construction and as many apparently 5 widely different embodiments of the invention could be made without departing from the scope thereof, it is intended that all matter set forth in the foregoing description or shown in the accompanying drawings shall 10 be interpreted as illustrative and not in a limiting sense.

What I claim is:—

1. In a finishing machine, in combination, a high speed burnishing tool, a low speed 15 pattern feed, and a pattern adapted to be moved by said pattern feed, said pattern comprising pattern feed engaging means and a clamping device which in operation exposes a marginal edge of the work to the 20 action of said tool.

2. In a finishing machine, in combination, a high speed finishing tool, a low speed pattern feed, and a pattern adapted to be moved by said pattern feed, said pattern 25 comprising pattern feed engaging means and a hinged clamping device which in operation exposes a marginal edge of the work to the action of said tool.

3. In a finishing machine, in combination, 30 a yieldable high speed finishing tool, a low speed pattern feed, and a pattern adapted to be correlated with said feed, said pattern comprising upper and lower relatively hinged clamping faces, having co-extensive 35 pattern edges, adapted to hold the work in operative position with a marginal edge thereof exposed to the action of said finishing tool.

4. In a finishing machine, in combination, 40 a yieldable high speed finishing tool, a low speed pattern feed, a pattern adapted to be correlated with said feed, said pattern comprising upper and lower relatively hinged clamping elements having co-operating 45 clamping faces and co-extensive pattern edges, adapted to hold the work in operative position with a marginal edge thereof exposed to the action of said finishing tool, and a feed templet positioned on the under 50 side of the lower clamping element.

5. In a finishing machine, in combination, 55 a yieldable high speed finishing tool, a low speed pattern feed, comprising a pair of rotary members yieldingly urged toward relative engagement, a pattern adapted to be correlated with said feed, said pattern comprising upper and lower relatively hinged clamping elements having clamping faces and co-extensive pattern edges, adapted 60 to hold the work in operative position with a marginal edge thereof exposed to the action of said finishing tool, and a feed templet positioned on the under side of the lower clamping element, adapted for movement between said rotary feed members.

6. In a finishing machine, in combination, a rotatable finishing tool, a table, a pattern adapted to be movably mounted on said table, said pattern comprising a feed-rail adapted to rest on said table, a pair of co-acting clamping faces at least one of which has a pattern edge, means for securing said faces in clamped relation with work between and an edge exposed, and means adapted to act upon said feed-rail to move the pattern 70 relatively to said tool so that said exposed edge is presented to the action thereof.

7. In combination, a rotatable edge finishing tool, a flat table, a pattern device adapted to be movably mounted on said table and comprising upper and lower work clamping faces, means to secure work therein with an edge exposed, pattern guiding means, and means for causing relative feeding movement between said tool and pattern device. 80

8. In combination, a rotatable edge finishing tool, a flat table, a pattern device adapted to be movably mounted on said table and comprising upper and lower work clamping faces, means to secure work therein with an edge exposed, pattern guiding means, means for causing relative feeding movement between said tool and pattern device, and quick operative means for moving said tool into and out of operative position in 90 order to allow said pattern to be presented and withdrawn.

9. In a finishing machine, the combination of a rotatable edge burnishing tool, work-holding means having provision for holding the edge to be burnished against bending when in engagement with the said burnishing tool and means for operating the said work-holding means so as to present the entire edge of the work progressively to 105 the action of the burnishing tool.

10. In a finishing machine, in combination, a high speed burnishing tool arranged in perpendicular relation to the work to be finished, a low speed pattern feed, and a 110 pattern adapted to be moved by said pattern feed, said pattern comprising pattern feed engaging means and a hinged clamping device which in operation exposes a marginal edge of the work to the action of said 115 tool.

11. In a finishing machine, in combination, a high speed finishing tool, means for heating said tool, a low speed pattern feed, and a pattern adapted to be moved by said 120 pattern feed, said pattern comprising pattern feed engaging means and a clamping device which in operation exposes a marginal edge of the work to the action of said tool.

12. In a finishing machine, in combination, a high speed finishing tool, means for heating said tool, a low speed pattern feed, and a pattern adapted to be moved by said 130 pattern feed and being so arranged as to

4
expose a marginal edge of the work to the action of said tool.

13. In a finishing machine, the combination of a rotating edge finishing tool, means for heating said tool, work-holding means having provision for holding the edge to be finished against bending when in engagement with said finishing tool and means for

operating the said work-holding means so as to present the entire edge of the work 10 progressively to the action of the finishing tool.

In witness whereof, I hereunto set my hand this twenty-eighth day of November, 1917.

WILLIAM F. PACKARD.
